(57) **CLAIM**

The ornamental design for a folding booklight, as shown and described.

DESCRIPTION

FIG. 1 is a top plan view of a folding booklight in a folded position and showing a preferred embodiment of our new design;

FIG. 2 is a bottom plan view thereof;

FIG. 3 is a right-side elevational view thereof; the left side being a mirror image thereof;

FIG. 4 is a front end view thereof;

FIG. 5 is a top perspective view thereof;

FIG. 6 is a bottom perspective view thereof;

FIG. 7 is a view similar to FIG. 5, but showing the booklight in an unfolded position; and,

FIG. 8 is a view similar to FIG. 3, but showing the booklight in an unfolded position.
